(57) CLAIM

The ornamental design for a display screen or portion thereof with icon, as shown and described.

DESCRIPTION

1. Display Screen or Portion Thereof with Icon

FIG. 1.1 is a front view of a display screen or portion thereof with icon showing my design; and

FIG. 1.2 is an enlarged view of the icon.

The broken lines illustrate a display screen or portion thereof and form no part of the claimed design.

The dotted broken lines in Fig. 1.1 form no part of the claimed design.
